UNITED STATES PATENT OFFICE.

JOSEPH H. McEVOY, OF HOUSTON, TEXAS.

WELL-STRAINER.

No. 828,956.

Specification of Letters Patent.

Patented Aug. 21, 1906.

Application filed November 11, 1905. Serial No. 286,901.

To all whom it may concern:

Be it known that I, JOSEPH H. McEVOY, a citizen of the United States, residing at Houston, in the county of Harris, State of Texas, have invented certain new and useful Improvements in Well-Strainers, of which the following is a specification, reference being had therein to the accompanying drawings.

This invention relates to a well-strainer, 10 and particularly to a cap or plug applied directly to an aperture in a pipe-section used for wells.

The invention has for an object to prevent the weakening of the pipe-section due to the 15 formation of apertures or slits therein and also the danger of destruction or injury to screens or wrapping carried upon the outer face of the straining-section of the piping.

With that object in view the present invention consists in a cap or plug disposed 20 within a suitable aperture in the pipe-section and provided with openings therethrough to effect a straining and filtering action in the passage of the water, oil, or other liquid into 25 the pipe-section. These caps or plugs completely fill the apertures and retain substantially the original strength of the pipe-section, so as to prevent binding or distortion thereof under pressure and also the closing of the 30 slotted sections due to similar pressure when formed directly in the wall of the pipe-section.

Other and further objects and advantages of the invention will be hereinafter set forth 35 and the novel features thereof defined by the appended claims.

In the drawings, Figure 1 is a perspective of a pipe-section having the invention applied thereto. Fig. 2 is a detail vertical section showing the application of several modification showing the application of several modified forms of the invention. Fig. 3 is a sectional perspective of one of the caps or 40 plugs. Fig. 4 is a perspective view of the cap shown in Fig. 3. Fig. 5 is a vertical section through the form shown in Fig. 4. Fig. 6 is a vertical section of a modified form having a holding-cap to retain a filtering-packing 45 in position. Fig. 7 is a similar view of the form shown in Fig. 6 with the cap separated and packing removed. Fig. 8 is a vertical section of a modified form of the invention 50 wherein a disk is used to retain the filtering-packing in position, and Fig. 9 is a similar view with the disk separated from the cap 55 and the packing removed therefrom.

Like numerals of reference denote like parts throughout the several views of the drawings.

The figure 1 designates a pipe-section provided with apertures of any desired configuration—for instance, circular, as herein shown. These apertures are adapted to be completely filled by a cap or plug 2, as shown in Figs. 3 and 4, which is forced and retained therein, so as to completely close the aperture and retain the original strength of the pipe-section. 60 These plugs are suitably apertured, so as to secure the desired straining action. For instance, slits or slots 3 may be extended across the face thereof and are outwardly flared at their inner portion, as shown at 4, so as to provide a clearance-space to prevent clogging of the slots by sand or other obstructing matter which may lodge therein. 65 These caps or plugs are provided with side walls 6, as shown in Fig. 3. The straining action is secured by the width of the slot, while the periphery of the cap retains the necessary strength to resist compression of the slots or slits and also to maintain the 70 strength of the pipe-section, which is essential owing to the extended length of the pipe therein and its weight.

Under some conditions of use it is desired to arrange the cap or plug so as to retain a filtering material of any desired character—for instance, as shown in Figs. 6 and 8. In Fig. 6 this material 7 is retained in position by the holding-cap 8, provided with slots or slits 9, similar in construction and arrangement to those of the cap 2, adapted to be inserted within the wall 6 thereof, thus forming a complete filtering-cap adapted for insertion in the pipe-apertures. A similar result may be obtained by the modified form of cap, 90 as shown at 10 in Fig. 8, where apertures 11 are provided in lieu of the slots 3 and similarly inwardly tapered to provide a clearance, while the filtering material 12 is disposed within the side wall 13 of the cap and retained by the disk 14, provided with apertures 15 therein to permit free passage of liquid therethrough.

It will be seen that when the caps or plugs are inserted in the apertures in the pipe-section either a strainer or filter may be provided therein, while the beveled configuration of the slots or apertures provides a clearance for any sand or other material which may tend to clog the strainer, and 105

when a filtering-packing is used all of the finer material is retained therein, so that the liquid entering the pipe-section is thoroughly filtered. It will also be apparent that in the 5 event of injury or destruction to any of these caps or plugs the same may be readily removed or replaced either for cleaning purposes or otherwise. These strainers or filters are particularly important in pumped wells 10 where the suction action disturbs the sand, causing the same to enter the pipe and injure the pump parts, as well as rendering the pumped liquid objectionable owing to its presence therein. The invention also obviates the use of gauze or wrappings applied 15 to the outer face of the pipe-sections, which are liable to become loose and detached in the operation of the pump or forcing of the pipe in position, particularly if the strainer-section when inserted strikes or contacts with any object within the well. It also obviates 20 the use of the slots or slits in the body of the pipe-section, by which the material is weakened so as to cause the bending or buckling 25 thereof and consequent distortion of the slits, as the plugs when inserted retain substantially the original strength of the section and comprise a strainer or filtering device wholly within the outer periphery of the 30 pipe, so as to be protected from injury and yet capable of most efficient action in the operation of the invention.

Having now described my invention and set forth its merits, what I claim, and desire 35 to secure by Letters Patent, is—

1. A straining cap or plug having a head provided with a circumferential side wall and

slits extending entirely across the said head, said slits extending downwardly through the head for the thickness thereof to leave intermediate solid portions of the head connected 40 to the side wall.

2. In a well-strainer, a cap or plug having straining-openings and a circumferential side wall, and an apertured closure-plate for 45 insertion within said side wall.

3. In a well-strainer, a cap having straining-openings and formed with a circumferential side wall, filtering-packing inserted within said cap, and apertured means disposed 50 within said side wall for retaining the packing in position.

4. In a well-strainer, a pipe-section provided with an aperture therein, a cap having straining-openings and formed with a circumferential side wall, a filtering-packing inserted 55 within said cap, and apertured means inserted within said side wall for retaining the packing in position.

5. In a well-strainer, a pipe-section provided with an aperture therein, a cap having straining-openings and formed with a circumferential side wall, a filtering-packing inserted 60 within said cap, and a cooperating apertured holding-cap having a side wall to be inserted within the side wall of the filtering-cap. 65

In testimony whereof I affix my signature in presence of two witnesses.

JOS. H. McEVOY.
